UNITED STATES PATENT OFFICE

1,979,430

METHOD OF FORMING SHAFTS FOR GOLF CLUBS

Carl Wright, Ashtabula, Ohio, assignor to The American Fork & Hoe Company, Geneva, Ohio, an organization of Ohio

Application March 19, 1932, Serial No. 599,955

9 Claims. (Cl. 29—156)

This invention relates to golf club shafts and the process of making the same, and pertains more particularly to tubular golf shafts made of steel or other like resilient material.

- 5 It has been before proposed to make golf club shafts of tubular steel or other resilient material and to provide certain torsional characteristics it has been proposed to form in the tube ribs, grooves or the like.
- 10 A shaft generally of this character is shown and described in the application for United States Letters Patent, filed by George B. Durell June 11, 1931, Serial No. 543,578.

In the process of making such shafts as heretofore proposed, for example that illustrated in the said pending application, inwardly directed grooves have been formed in the metal tube by dies and die operating mechanisms which press or draw the wall of the tube inwardly, beginning 20 at a point spaced from the end of the tube and extending longitudinally over the tube for a predetermined desirable distance; and thereafter the tube has been tapered, by steps or otherwise, by other dies and die operating mechanisms.

- 25 The instant invention relates particularly to the method of forming the grooves in the tube blank and for subsequently tapering the tube, the latter operation preferably being such as to taper the tube in successive steps of successively 30 smaller diameter.

It is therefore an object of this invention to provide an improved tubular golf club shaft.

Another object of the invention is to provide an improved method of forming metallic tubular 35 golf club shafts having properly graduated torsional characteristics in the different longitudinally disposed portions of the shaft.

Another object of my invention is to provide an improved method of making metal tubular 40 golf club shafts of superior quality and operating characteristics.

Another object of my invention is to provide an improved method of making a metallic tubular golf club shaft of the type having inwardly 45 directed longitudinally extending ribs.

Other objects will be apparent to those skilled in the art to which my invention appertains.

My invention is fully disclosed in the following description taken in connection with the accompanying drawing, in which:

Fig. 1 is an elevational view of a golf club shaft embodying my invention and illustrating in broken lines a club head which may be associated therewith;

55 Fig. 2 is an elevational view approximately full

size of a tubular blank from which a shaft of my invention may be formed;

Fig. 3 is a view illustrating an initial drawing operation which may be performed on the blank of Fig. 2 in forming the shaft of Fig. 1.

Fig. 4 is a view illustrating the performance of another operation succeeding that of Fig. 3;

Fig. 5 is a view illustrating a part of a die mechanism which I may employ in performing the operation of Fig. 4;

Fig. 6 is a view illustrating in longitudinal cross-section, the metal tube after the operation of Fig. 4 has been performed thereon;

Fig. 7 is a cross-sectional view taken approximately from the plane 7—7 of Fig. 6;

Figs. 8, 9 and 10 are views illustrating, respectively, the apparatus for and manner of performing three representative operations which may be successively performed on the tube of Fig. 6;

Figs. 11, 12 and 13 are views taken approximately from the planes 11, 12 and 13, respectively, of Figs. 8, 9 and 10;

Fig. 14 is a view taken approximately from the plane 14 of Fig. 2;

Fig. 15 is a fragmentary view similar to a part 80 of Fig. 1 but showing a modification.

Referring to Fig. 1 of the drawing, I have illustrated therein a tubular golf shaft made in accordance with my invention, and comprising a plurality of integrally formed substantially cylindrical tubular sections extending longitudinally of the shaft from a section 2 of least diameter, through intermediate sections of progressively increased diameter such as the sections 3, 4, 5 etc., until the larger end of the shaft is reached where 90 it terminates in a cylindrical section 6 which may be suitably covered with a wrapping of leather or other hand-grip covering material according to the ordinary practice. Preferably, a large number of the stepped sections, such as 3, 4, 5 95 etc., is provided, the usual number being about seventeen sections although this number may be varied.

The tubular section 2 in the preferred embodiment of my invention is preferably made of greater length than the adjacent sections of progressively larger diameter.

Internally, the shaft is provided with internal ribs 7—7, preferably four in number, and equally spaced, although the number and the spacing 105 may be varied, the ribs extending from a point on the tube section 2 preferably longitudinally spaced from the end 8 of the tube as at 9, Fig. 1, and proceeding longitudinally of the shaft over a suitable extent of the stepped length of the 110

shaft as, for example, to the point 12, Fig. 1, adjacent the upper end of the thirteenth section. The ribs essentially comprise infolded portions of the lateral wall of the tube. The inward radial extent of the ribs is greater in the smallest section, as for example, the section 2, and progressively decreases proceeding from the section 2 upwardly of the shaft as viewed in the drawing. The difference in the inward radial extent of the ribs as well as the difference in their circumferential configuration is plainly shown in the drawing; Fig. 14 illustrates the ribs 7 at approximately the plane 12 of Fig. 1.

In a similar manner, the cross-sectional showing 15 of the tube and ribs in Fig. 13 illustrates the ribs and the tube at approximately the plane 13 of Fig. 1 and the cross-sectional part of Fig. 11 illustrates the tube and the ribs 7 at approximately the plane 11 of Fig. 1.

20 In folding in the wall of the tube to compose the ribs 7, the material of the tube wall is so operated upon that the fold composing the ribs is outwardly open as shown at 13. Thus the external surface of the shaft is not a continuous cylindrical surface at any point or portion coextensive with the grooves 7 but is longitudinally broken by fissures or circumferentially narrow grooves corresponding to each rib. Proceeding upwardly along the ribs, these external grooves 25 or fissures in the wall of the shaft, generally indicated at 13, are progressively wider being at their maximum width at the upper end 12 thereof and as illustrated in the drawing.

I have found that a golf club having a handle 35 shaft of the above described ribbed tubular structure, when used in play, reacts to the lateral strains and to the torsional strains set up therein very much in the same manner as the old prior hickory shaft.

40 I have found also that the lateral or transverse bending stresses put upon the shaft are absorbed by the ribs 7 in generally the same manner whether the folds composing the ribs are entirely closed together at the surface of the shaft or 45 whether they are open as shown generally at 13; but I have also found that the torsional stresses applied to the shaft in play are absorbed in a manner more nearly, if not exactly, like that in the hickory shaft, if, in forming the ribs, the 50 grooves or fissures above described and shown generally at 13, are left of substantial circumferential width, that is, are outwardly open as indicated at 13.

By leaving open grooves or fissures 13 in the 55 outer surface of the tubular shaft, a torsional resilience is introduced into the shaft apparently due to the fact that under torsional strain, the grooves or fissures 13 may resiliently open and close to slight degrees. Each of the ribs is in a 60 cross-section of generally U-shape and can to a degree perform the functions of a U-shaped or hairpin spring, the sides of the U moving closer together or farther apart resiliently as torsion is put upon the shaft and released respectively.

65 By terminating the longitudinal fissures 13 and ribs 7 at a point spaced from the end 8 of the shaft, as for example at 9, an ungrooved unribbed portion 14 is left to which the club head may be secured, and I have found that the transmission 70 of the stresses from the club head into the handle shaft is effected more efficiently if transmitted first into a continuous portion 14 of circular cross-section than into a groove or ribbed portion, which would be the case if the grooves 75 and ribs were extended to the end 8 of the shaft,

particularly when it is desired to leave the fissures or grooves open as at 13. Furthermore, a more secure and durable connection between the hosel 41 of the club head and the end of the shaft may be effected upon a shaft section or shaft end having circular cross-section than upon a grooved one.

The extent upwardly along the shaft to which the ribs and outwardly open grooves or fissures 13 are carried may be varied.

The preferred process of making a shaft such as illustrated in Fig. 1 is as follows. A cylindrical tube of the required diameter such as illustrated in Fig. 2, to provide the handle end section 6 is operated upon by a die apparatus such as illustrated in Fig. 3, and the tube indicated at 15 is drawn in the direction of the arrow 16 through a die pass 17 to produce on the end of the tube 15 a section of reduced diameter 18 approximately of the same length as the ungrooved portion 14 of the finished club shaft, that is, the portion between the end 8 of the finished shaft and the beginning of the grooves therein at 9.

The tube is then removed from the die 19 having the die pass 17 and is next operated upon by a die apparatus such as illustrated in Figs. 4 and 5. The tube indicated at 15 is drawn in the direction of the arrow 20 through a die pass consisting of a plurality such as four circumferentially spaced balls 23-23. The balls 23 are so disposed in a die element 24 that the diameter determined by a circle tangent to their inwardly projecting surfaces is approximately the diameter of the reduced portion 18. The balls 23 may be mounted in their die element 24 in any suitable manner but, as illustrated, are disposed in suitable recesses 25 formed in an inner cylindrical wall 26 of the die element 24, and may be retained therein against longitudinal movement in one direction by shoulders 27 of the recesses 25 and in the other direction by superimposed plates 28.

The movement of the tube 15 through the die pass balls 23 may be continued over the length of the tube 15 to the extent desired for the 120 grooves 7 as, for example, to the point 12, Fig. 1. A suitable configuration for the ribs 7 is shown in Fig. 7.

Having provided the ribs 7 as thus described, and the tube having been withdrawn from the 125 ball die pass, the tube is then projected through a plurality of dies by successive operations to provide the successive stepped sections above referred to of successively smaller diameter. In Figs. 8, 9 and 10 and in Figs. 11, 12 and 13, I 130 have illustrated a number of successive dies by which the successively smaller diameter sections of the stepped tube may be formed, together with fragmentary portions of the tube itself, illustrating the successive reduction and the production thereon of the shoulders intermediate each adjacent pair of sections, and the formation of the ribs within the tube.

In Fig. 8 at 31 is indicated a portion of the tube section 2 before drawing the same and at 32 one 140 of the grooves formed therein by the die apparatus of Figs. 4 and 5. At 33 is the drawing die through which the tube is drawn longitudinally, reducing its diameter to that shown at 34 and partly closing up the groove as at 35. In Fig. 11 145 is shown the shape of the groove 35 at this time.

In the succeeding Figures 9 to 13 inclusive, successive reductions of the tube to the final diameter of the section 2, Figs. 10 and 13, is illustrated together with the successive changes 150

in the shape internally and externally of the ribs and grooves, respectively, ending finally in the cross-sectional configuration of Fig. 13. As shown in this figure, inwardly the grooves have 5 become the ribs 7 and outwardly the grooves have been almost entirely closed up leaving the longitudinal openings or crevices 13.

It is not intended that the Figures 8 to 13 illustrate successive sections of the golf shaft of Fig. 1, but that they illustrate successive phases 10 of the tube and of the grooves therein during the successive drawing operations on the tube to produce the stepped sections. However, the relative sizes of the tube and the relative configurations 15 of the ribs 7 shown in Figs. 11 to 13 inclusive are approximately those of the tube of Fig. 1 as considered taken from the planes 11, 12 and 13 there- of respectively.

The head 40 or hosel 41 thereof may be at- 20 tached to the section 2 after it has finally been drawn through the last die and while it is in its cylindrical form.

In some cases, it may be desirable to attach 25 the hosel 41 to the section 2 with the ribs 7 ex- tending into the hosel. In such a case, the sec- tion 2, after the ribs have been formed therein, may be cut off, for example at the point 9 of Fig. 1, and the ribbed end of the section 2 thus formed may be inserted in the hosel 41 and 30 secured thereto. This is illustrated in Fig. 15.

To perform the operation of drawing above de- 35 scribed, one type of apparatus which may be employed to effect this operation is described in United States Letters Patent No. 1,670,530, dated May 22, 1928, for Golf shafts, issued to Robert H. Cowdery; or in the pending application of Robert H. Cowdery, Serial No. 447,878, filed April 28, 1930.

Again, in some cases, it may be desired to form 40 the section 2 by a drawing operation to taper it from substantially its conjunction with the section 3 to its end 8. This operation may be performed in drawing die and apparatus such as illustrated and described in the copending appli- 45 cation of Birney C. Batcheller, Serial No. 268,130, filed April 7, 1928, to which reference may be had for a complete description of the contracting re- ducing die mechanism adaptable for use in the formation of tapered tubes or rods.

50 The compressive reduction operation accom- plished by such apparatus upon the tube section 2 to reform it to taper form, tends to increase the degree of closure of the previously formed grooves or fissures 13 in the section tube, but not entirely close them for the purposes hereinbefore set forth.

55 My invention comprehends golf club handle shafts which are not stepped as hereinbefore de- scribed, but which have a gradual taper toward the head. To produce such a shaft embodying my invention, a cylindrical tube may have grooves 60 formed therein by a die pass apparatus such as that shown in Figs. 4 and 5 herein, and then the cylindrical tube may be reduced to a tapered tube of smaller diameter to provide a tapering golf handle shaft with partly closed grooves therein. The apparatus to taper such a grooved shaft may be that described fully in the above-mentioned Batcheller application.

70 Again, the advantages obtained in a handle shaft of this type resulting from the provision of internal ribs and corresponding external grooves or crevices which are not entirely closed up on the external surface of the shaft, may be 75 obtained and enjoyed in a shaft in which the

grooves are entirely closed tight by the tapering or stepping die operation on all of a part of the extent of the groove.

In the foregoing described method of making the shaft, it will be observed that by forming 80 on the end of the tube a portion of reduced diameter, the grooves can subsequently be formed in the portion of unreduced diameter by a die pass, such as a ball pass, of constant diameter, thus obviating the necessity of a die mechanism whereby the diameter of the pass can be reduced to form the grooves as would be the case if the grooves were formed in a tube of substantially uniform diameter. In this connection, the portion of reduced diameter may be of various rel- 85 atively smaller diameters and it is not essential that this diameter shall be, as illustrated and de- scribed hereinbefore, substantially the same as the diameter of the ball die pass.

In other respects my invention is not limited 90 to the exact details of apparatus and the result- ant shaft structure above shown and described and many other modifications and changes may be made therein within the spirit and scope of my invention without sacrificing its advantages. 100

I claim:

1. The method of making a golf club shaft which includes performing a longitudinal die drawing operation upon a seamless tubular blank to provide a portion of reduced diameter, form- 105 ing in the wall of the unreduced portion by a longitudinal die drawing operation a plurality of circumferentially spaced outwardly flaring recesses, then longitudinally die drawing the tube to concurrently close up the sides of the recesses 110 to dispose them mutually adjacent but out of mutual contact and to form inwardly projecting, longitudinally extending ribs coextensive with the recesses.

2. The method of making a golf club shaft 115 which includes performing a longitudinal die drawing operation upon a seamless tubular blank to provide a portion of reduced diameter, form- ing in the wall of the unreduced portion by a longitudinal die drawing operation a plurality of 120 circumferentially spaced outwardly flaring recesses beginning at the juncture of the reduced and unreduced portions, then longitudinally die drawing the tube to render it of successively smaller diameter at spaced points successively nearer the 125 reduced end and to circumferentially close up the sides of the recesses to dispose them mutually adjacent but out of mutual contact, and to form inwardly projecting longitudinally extending ribs coextensive with the recesses. 130

3. The method of making a golf club shaft which includes performing a longitudinal die drawing operation upon a tubular blank to pro- 135 vide a portion of reduced diameter at one end of the blank, forming in the wall of the unre- duced portion by a longitudinal die drawing op- eration a plurality of circumferentially spaced outwardly flaring recesses beginning at the jun- 140 ture of the reduced and unreduced portions and terminating at a point longitudinally spaced from the opposite end of the tube blank, then longitudinally die drawing the tube to concurrently close up the sides of the recesses to dispose them mutually adjacent but out of mutual contact and to form inwardly projecting longitudinally ex- 145 tends ribs coextensive with the recesses.

4. The method of making a golf club shaft which includes performing a longitudinal die drawing operation upon a tubular blank to pro- 150 vide a portion of reduced diameter at one end,

- forming in the wall of the unreduced portion by a longitudinal die drawing operation a plurality of circumferentially spaced outwardly flaring recesses, then operating upon the tube with a succession of drawing dies of successively smaller diameter to generally taper the tube toward the reduced end by drawing the tube into a longitudinal series of substantially cylindrical sections of successively smaller diameter and thereby concurrently closing up the sides of the recesses to dispose them mutually adjacent but out of mutual contact and to form inwardly projecting longitudinally extending ribs coextensive with the recesses. 5

15 5. The method of making a golf club shaft which includes performing a longitudinal die drawing operation upon a tubular blank to provide a portion of reduced diameter at one end, forming in the wall of the unreduced portion by a longitudinal die drawing operation a plurality of circumferentially spaced outwardly flaring recesses, the recesses beginning at the juncture of the reduced and unreduced portions, then operating upon the tube with a succession of drawing dies of successively smaller diameter to generally taper the tube toward the end from which the recesses begin by drawing the tube into a longitudinal series of substantially cylindrical sections of successively smaller diameter and thereby concurrently closing up the sides of the recesses to dispose them mutually adjacent but out of mutual contact and to form inwardly projecting longitudinally extending ribs coextensive with the recesses. 20

25 6. The method of making a golf club shaft which includes performing a longitudinal die drawing operation upon a tubular blank to provide a portion of reduced diameter at one end, forming in the wall of the unreduced portion by a longitudinal die drawing operation a plurality of circumferentially spaced outwardly flaring recesses beginning at the juncture of the reduced and unreduced portions, then longitudinally die drawing the tube with a succession of drawing dies to taper the tube toward the end at which

30 the recesses begin by drawing the tube into a longitudinal series of substantially cylindrical sections of successively smaller diameters and thereby concurrently closing up the sides of the recesses to dispose them mutually adjacent but out of mutual contact and to form inwardly projecting longitudinally extending ribs coextensive with the recesses. 25

35 7. The method of making a golf club shaft which includes providing a tubular blank having portions of unequal diameter, forming in the wall of the portion of larger diameter by a longitudinal die drawing operation a plurality of circumferentially spaced outwardly open recesses, then longitudinally die drawing the tube to concurrently close up the sides of the recesses and to form inwardly projecting longitudinally extending ribs coextensive with the recesses. 30

40 8. The method of making a golf club shaft which includes providing a tubular blank having portions of unequal diameter, forming in the wall of the portion of larger diameter by a longitudinal die drawing operation a plurality of circumferentially spaced outwardly open recesses, then operating upon the tube with a succession of drawing dies of successively smaller diameter to generally taper the tube toward the reduced end by drawing the tube into a longitudinal series of substantially cylindrical sections of successively smaller diameters. 35

45 9. The method of making golf club shafts which includes performing a longitudinal die drawing operation upon a seamless tubular blank to provide a portion of reduced diameter, forming in the wall of the unreduced portion by a longitudinal die drawing operation an outwardly flaring recess, then longitudinally die drawing the tube to concurrently close up the sides of the recess to dispose them mutually adjacent but out of mutual contact and to form an inwardly projecting longitudinally extending rib co-extensive with the recess. 40
